DOOR FOR STOCK CARS

Carl E. Eklind and Kenneth J. Tobin, Chicago,
Ill., assignors, by mesne assignments, to The
Youngstown Steel Door Company, Cleveland,
Ohio, a corporation of Ohio

Original application April 22, 1929, Serial No.
356,971, now Patent No. 1,925,375, dated Sep-
tember 5, 1933. Divided and this application
July 26, 1933, Serial No. 682,303

10 Claims. (Cl. 20—23)

This invention relates to doors for stock cars. It is common practice at the present time to make such doors of wood. They usually consist of wooden stiles and rails with spaced transverse slats connecting the stiles. These slats are frequently broken by the animals within the car and to renew the same, it is necessary to remove the doors. One feature of this invention seeks to eliminate the necessity for removing the door, 5 when it is desired to replace a broken slat.

Some doors of this character use metal binding strips over the outside of the door and these binding strips must be removed before a broken slat can be replaced. This invention also overcomes this objection.

A further objection to present doors for stock cars lies in the locking arrangement which generally consists of staples upon the door posts and hasps upon the door for engaging staples. It 20 will readily be appreciated that the bottom of the door must be pulled outwardly to pass the staples and as the doors are moved past the staples during their opening and closing movements they become chafed by such staples with the result 25 that it becomes necessary to renew parts of the door in a very short time. Another feature of this invention resides in means for eliminating such chafing of the inside of the door.

The lower margins of doors for stock cars are 30 usually secured by chains that allow the doors to be pulled outwardly a limited extent. These chains usually become tangled and retard the movement of the door. This objection is eliminated in the use of single links or the like.

It also frequently happens that the bedding 35 and refuse in the stock cars becomes frozen to the floor and door, making it impossible to operate the door. To overcome this objection a metal chafing strip is attached to the lower margin of 40 the door.

The invention comprises the novel structure and combination of parts hereinafter described and more particularly pointed out and defined in the appended claims.

In the accompanying drawings which illustrate 45 a preferred form of this invention and in which similar reference numerals refer to similar features in the different views:

Figure 1 is a fragmentary side elevational view 50 of a stock car embodying a door involving this invention.

Figure 2 is an enlarged and broken sectional view taken upon the line II—II of Figure 1.

Figure 3 is a view similar to Figure 2 showing 55 the door in its pulled out position.

Figure 4 is an enlarged fragmentary sectional view taken upon the line IV—IV of Figure 1.

This application is a division of co-pending application, Serial No. 356,971, filed April 22, 1929, now Patent No. 1,925,375, dated September 5, 1933.

The door involving this invention comprises a frame consisting of an upper metal rail 1, which is shown in the form of a Z bar, a lower metal rail 2, which is in the form of a T bar and metal side stiles 3 which are in the form of angle bars. 10 These frame members are suitably secured together. To the lower corners of the frame are secured gusset plates 4. To the upper corners of the frame are secured roller hangers 5. Diagonally arranged metal braces 6, which cross each other at approximately their central points, connect the gussets 4 with the hangers 5. Transverse wooden slats 7 in spaced relation are 15 removably bolted to the stiles 3 and braces 6 by removable bolts 8. It will be noted that the slats 20 are seated in the angles of the stiles and are protected thereby. Consequently, if a slat becomes 25 broken it is only necessary to remove the bolts 8 and take off the old slat and replace the same without removing the door from the car.

Between the door posts 9 (Figures 1 and 4) there extends a rod 10 which is attached to the Z bars 11 which are attached to the posts. A second rod 12 is attached at its forward end to 30 the rear Z bar 11 and extends rearwardly a distance substantially equal to the width of the door where it is attached to the side of the car as indicated at 13. In alignment with the attaching means 13, are stops 14 for arresting the 35 door in its open position.

The front end of the lower rail 2 carries a link 15 that encircles the rod 10 and the rear end of said rail carries a second link 16 that encircles the rod 12. This second link 16 is somewhat 40 shorter than the first link since it will be noted that rod 12 is positioned outwardly from the rod 10.

The door is latched at its front end by a hasp 17 which is secured to the door and which engages a staple 18 on the front door post. The rear end of the door is latched by a jointed hasp 19, one section of which is anchored upon a staple 20 upon the rear side of the rear post 9 (Figure 4). The other section of the hasp 19 engages 45 a staple 21 upon the door. It will be noted that the joint 19a of the sections is approximately opposite the rear corner of the door. This jointed latch tends to hold the door inwardly. When it is desired to open the door the hasp 19 is 50 55

unlatched and swung rearwardly behind the rear post 9, where it will be out of the path of the door in its opening movement.

The lower slat 7 of the door carries a chafing plate 22 upon its inner side and directly opposite the edge of the floor. This plate 22 will tend to prevent the door from becoming frozen to the bedding and refuse that is apt to be trodden out between the door and floor.

10 From the foregoing, it will be apparent that the door involving this invention eliminates many of the objectionable features of stock car doors heretofore used, and at the same time facilitates the repair of such doors.

15 We claim as our invention:

1. In a stock car, a pair of spaced rods, a sliding door, said rods extending in the direction of opening movement of said door, a link upon the forward end of said door and encircling one rod, and 20 a link upon rear end of said door encircling the other rod, said links moving along said rods during the sliding movement of said door.

2. In a stock car, a pair of spaced rods, a sliding door, said rods extending in the direction of 25 opening movement of said door, a link upon the forward end of the door encircling one rod, a second link upon the rear end of said door encircling the other rod, said links moving along said rods during the sliding movement of said door, and a chafing plate upon the inner lower 30 surface of said door.

3. In a stock car, a sliding door having a lower rail, a single link pivoted to the forward part of 35 said rail, a longer single link pivoted to the rear portion of said rail, a guide rod extending in the direction of opening movement of said door upon the car for receiving the first link and a second guide rod on the car extending in the direction of opening movement of said door spaced outwardly of the first guide rod for receiving and guiding the second link, said links moving along 40 said rods during the sliding movement of said door.

4. In a stock car having a side door opening, 45 a track secured to said car above said opening, a stock car door for closing said opening, hangers secured to said door for supporting said door for longitudinal movement upon said track, said hangers being capable of slight transverse rocking movement upon said track, whereby said door may be rocked away from said car, in combination with means for limiting the outward movement of the lower portion of said door, said means comprising a longitudinally extending rod 50 secured to said car and a link, said link extending through an opening provided in the lower margin of said door and embracing said rod, said link being movable along said rod during the longitudinal movement of said door.

5. In a stock car having a door opening, a top 55 supported sliding door for closing said opening, a single link secured to each of the lower corners of said door and longitudinally extending means secured to said car below the door opening, said links embracing said means and being movable there-along, for the purpose set forth.

6. In a stock car having a door opening and a floor extending outwardly beyond said opening, a top supported sliding door for closing said opening, a single link secured to each of the lower corners of said door and means secured to said

car below said door opening providing a longitudinally extending rod for each of said links, said rods being embraced by said links, said floor extension being disposed in protective relationship to one of said rods, said links being movable along said rods during the sliding movement of said door. 5

7. In a stock car having a side door opening, a track secured to said car above said opening, a stock car door for closing said opening, hangers 10 secured to said door for supporting said door for longitudinal movement upon said track, said hangers being capable of slight transverse rocking movement upon said track, whereby said door may be rocked away from said car, in combination with longitudinally extending means secured to said car below said door, a single link swingably secured to the lower margin of the door adjacent to the front vertical edge thereof, a single link swingably secured to the lower margin of the 20 door adjacent to the rear vertical edge thereof, each of said links embracing said longitudinally extending means and being slidably there-along for the purpose set forth. 15

8. In a stock car having a side door opening, a 25 track secured to said car above said opening, a stock car door for closing said opening, hangers secured to said door for supporting said door for longitudinal movement upon said track, said hangers being capable of slight transverse rocking 30 movement upon said track whereby said door may be rocked away from said car, in combination with means for limiting the outward movement of the lower portion of said door, said means comprising a longitudinally extending rod 35 secured to said car and a link, said link extending through an opening provided in the lower margin of said door and embracing said rod, said link being movable along said rod during the longitudinal movement of said door. 40

9. In a stock car having a side door opening, a track secured to said car above said opening, a stock car door for closing said opening, hangers secured to said door for supporting said door for longitudinal movement upon said track, said 45 hangers being capable of slight transverse rocking movement upon said track whereby said door may be rocked away from said car, in combination with means for limiting the outward movement of the lower portion of said door, said means comprising a longitudinally extending rod 50 secured to said car and a link, said link being swingably secured to the lower margin of said door and extending through an opening provided in said margin, said link slidably embracing said 55 rod.

10. In a railway car having a side door opening, a track secured to said car above said opening, means supporting said door for longitudinal movement along said track and for rocking movement transversely of said track, whereby the lower portion of said door may be moved away from said car, in combination with means for limiting the outward movement of said lower portion of the door, said means comprising a 60 longitudinally extending rod secured to said car and a link, said link being secured directly to said lower portion of the door and slidably embracing said rod. 65
